DESIGN FOR EMBROIDERED DRESS TRIMMING

Emil Prazak, Elizabeth, N. J.

Application October 12, 1934, Serial No. 53,601

Term of patent 7 years

To all whom it may concern:

Be it known that I, Emil Prazak, a citizen of the United States, residing at Elizabeth, in the county of Union and State of New Jersey, have invented a new, original, and ornamental Design for Embroidered Dress Trimming, of which the following is a specification, reference being had to the accompanying drawing, forming part hereof.

The said drawing shows a face or plan view of the embroidered dress trimming embodying my new design.

The dominant features comprising my design

are characterized by embroidery having a background consisting of shirred fabric having equally spaced, parallel rows of stitching extending longitudinally thereof, the embroidery design being composed of a plurality of independent zig-zag stitches disposed between the parallel rows of stitching, said zig-zag stitches being partially concealed by the folds of the shirred fabric.

I claim:

The ornamental design for embroidered dress trimming as shown and described.

EMIL PRAZAK.
